(57) **CLAIM**

The ornamental design for a flashlight, as shown and described.

DESCRIPTION

FIG. 1 is a top-side perspective view of the flashlight, showing my new design;

FIG. 2 is a bottom-side perspective view thereof;

FIG. 3 is front elevation view thereof;

FIG. 4 is a rear elevation view thereof;

FIG. 5 is a left side elevation view thereof;

FIG. 6 is a right side elevation view thereof;

FIG. 7 is a top elevation view thereof, wherein it is further illustrated how the slant of the flashlight may bring the bottom into view; and,

FIG. 8 is a bottom elevation view thereof, wherein it is further illustrated how the slant of the flashlight may bring the bend of the flashlight into view.
